AUTOMATIC EMERGENCY LIGHT CONTROL
SYSTEMKogen Matsukawa, Ewa, Honolulu, Territory of
Hawaii

Application February 23, 1940, Serial No. 320,519

5 Claims. (Cl. 200—113)

The present invention appertains to new and useful improvements in lighting systems and more particularly to an emergency light control system, the principal object of the invention being to provide a system which will operate automatically, or which can be operated manually.

Another important object of the invention is to provide a system of the character stated especially adapted for automobile headlight use, the same being operative to automatically change over from high beam to low beam in the event the high beam circuit becomes disrupted, or on the other hand, change over from low beam to high beam in the event the low beam circuit becomes defective.

Other objects and advantages of the invention will become apparent to the reader of the following specification.

In the drawings:

Figure 1 represents a perspective view of the automatic means.

Figure 2 is a vertical sectional view through the automatic means.

Figure 3 is a perspective view of the manual switch.

Figure 4 is a diagrammatic view disclosing the electrical connection between the electrical devices involved.

Referring to the drawings, wherein like numerals designate like parts, it can be seen that numeral 5 represents the base of insulation while numeral 6 denotes the back panel.

Mounted on blocks 7 on the panel 6 are the brackets 7 through which are slidably disposed the stems 9 carrying the contacts 10 and interposed between these contacts 10 and the brackets 8 are the compression springs 11. These contacts 10 are normally bridged by the bridge plate 12 which is secured by screws 13 to the upper end of the plunger generally referred to by numeral 14, this plunger consisting of the upper wooden section 15 and the lower metallic weight-forming section 16, the latter being formed with a socket at its upper end for receiving the reduced depending portion 17 of the upper section 15. The plunger 14 is movable in a cylinder 18 which is provided with a pair of slots 19—19 at diametrically opposite side portions thereof and which extend from a point near the lower end of the cylinder upwardly to open through the upper end. The end portions of the bridge plate 12 are guided by these slots 19.

A stem 20 extends upwardly from the bridge plate 12 and has an eye 21 at its upper end be-

tween which and the binding post 22 is interposed the fuse 23.

The cylinder 18 is secured by the clamp 24 to the panel 6 by screws or the like 25. The contacts 10 and bridge plate 12, of course take care of one circuit of the system shown in Figure 4, depending upon the position of the manually operable switch A.

The switch generally referred to by numeral 10 26 consists of the rocker 29 fulcrumed as at 30 on the support 31. One end of the rocker 29 has the plate-like formation 32 disposed under the cylinder 18. The other end is provided with the lateral flanges 33 to limit downward movement of the rocker 29 against the upper ends of the contact members 34 and 35, it being understood, of course, that this rocker 29 is of insulating material.

At each side of the rocker 29 is located a pair 20 of posts 36—37, rising from the base 5. Each of these posts 36—37 has an inwardly and downwardly disposed head portion 38 through which a slide pin 39 is disposed. A compression spring 40 is interposed between each of these heads 38 25 and the contacts 34 and 35 carried by the corresponding pin. Normally the outer end of the rocker 29 is interposed between the contacts 34 and 35, as shown in Figure 1.

The manually controlled switch generally referred to by numeral A consists of the base 45 on which are the pair of upstanding brackets 46—46 through the upper portions of which are slidably disposed members 47 carrying contacts 48 and 49. On each of the slide members 47 35 and between each contact 48 or 49 and the bracket proper is a coiled compression spring 50.

On the intermediate portion of the base 45 is swingably mounted the block 51 of insulation. A blade 52 extends in one direction from the 40 block 51 and has the bifurcated end 53 secured to the block 51 while its opposite end is engageable with one or the other of the contacts 48—49.

The blade 54 is provided with the bifurcated head 55 which is secured to the other end of the 45 block 51. The blade 54 is operative between the contacts 56 and 57 which are located on the slide stems 58 slidably disposed against the action of compression springs 59 on the bracket 60—60. A joint of insulation 61 connects the blade 54 with 50 the handle 62 and this handle 62 is operative along the horizontal plate 63 which is supported by compression spring 64. A bridge member 65 is disposed over the plate 63 and is provided with offsets 66 and 67 therein into one or the other of which the handle 62 is engageable.

As is shown in Figure 4, numeral 68 represents the source of current which extends to the switch 69. From the switch 69 current can pass by way of the conductor 70 to the fuse 23 and from there by way of the stem 20 to the bridge member 12 and contacts 10. Current can then pass from the contacts 10 by way of the jumper 71 to the blade 54. If the handle 62 is toward the right as shown in Figure 3, the blade 54 will be engaging the contact 57 and the low beam filament 72 will be energized. Should the fuse 23 become disrupted, then the current will pass along the conductor 73, and as the plunger 14 has fallen to lift the rocker 29 and permit the contacts of the contacts 34 and 35 to come together, current will flow across contacts 34 and 35 and fuse 74 to the jumper 75 and switch blade 52 and as the blade 52 will be engaged with the contact 48, current will flow to the high beam filament 76.

While the foregoing specification sets forth the invention in specific terms, it is to be understood that numerous changes in the shape, size and materials may be resorted to without departing from the spirit and scope of the invention as claimed hereinafter.

Having thus described the invention, what is claimed as new is:

1. A switch of the character described comprising a gravitable body, a contact bridge carried by the body, a pair of contacts adapted to be bridged by the bridge member when the gravitable body is in elevated position, a fuse for suspending the body in a position holding the bridge member against the contacts, a second pair of contacts, spring means for bringing the last-mentioned contacts together, a spacer of insulation interposed between the last-mentioned contacts, said spacer being movably mounted and adapted to be displaced from between the last-mentioned contacts when the weight of the gravitable body is released against the same and pursuant to the disruption of the fuse.

2. A switch of the character described comprising a gravitable body, a contact bridge carried by the body, a pair of contacts adapted to be bridged by the bridge member when the gravitable body is in elevated position, a fuse for suspending the body in a position holding the bridge member against the contacts, a second pair of contacts, spring means for bringing the last-mentioned contacts together, a spacer of insulation interposed between the last-mentioned contacts, said spacer being movably mounted and adapted to be displaced from between the last-mentioned contacts when the weight of the gravitable body is released against the same and pursuant to the disruption of the fuse, an L-shaped support, the first-mentioned pair of contacts being mounted on the vertical portion of the support, a guide on the vertical portion of the support for the gravitable body, the second-mentioned pair of contacts

being mounted on the horizontal portion of the support.

3. A switch of the character described comprising a gravitable body, a contact bridge carried by the body, a pair of contacts adapted to be bridged by the bridge member when the gravitable body is in elevated position, a fuse for suspending the body in a position holding the bridge member against the contacts, a second pair of contacts, spring means for bringing the last-mentioned contacts together, a spacer of insulation interposed between the last-mentioned contacts, said spacer being movably mounted and adapted to be displaced from between the last-mentioned contacts when the weight of the gravitable body is released against the same and pursuant to the disruption of the fuse, an L-shaped support, the first-mentioned pair of contacts being mounted on the vertical portion of the support, a guide on the vertical portion of the support for the gravitable body, the second-mentioned pair of contacts being mounted on the horizontal portion of the support, said spacer being rockably supported on the horizontal portion of the support.

25 4. A switch of the character described comprising a gravitable body, a contact bridge carried by the body, a pair of contacts adapted to be bridged by the bridge member when the gravitable body is in elevated position, a fuse for suspending the body in a position holding the bridge member against the contacts, a second pair of contacts, spring means for bringing the last-mentioned contacts together, a spacer of insulation interposed between the last-mentioned contacts, said spacer being movably mounted and adapted to be displaced from between the last-mentioned contacts when the weight of the gravitable body is released against the same and pursuant to the disruption of the fuse, a guide for the gravitable body, said guide being slotted to accommodate the bridge member carried by the gravitable body.

5. A switch of the character described comprising a gravitable body, a contact bridge carried by the body, a pair of contacts adapted to be bridged by the bridge member when the gravitable body is in elevated position, a fuse for suspending the body in a position holding the bridge member against the contacts, a second pair of contacts, spring means for bringing the last-mentioned contacts together, a spacer of insulation interposed between the last-mentioned contacts, said spacer being movably mounted and adapted to be displaced from between the last-mentioned contacts when the weight of the gravitable body is released against the same and pursuant to the disruption of the fuse, said first-mentioned pair of contacts being provided with spring means for urging the same against the bridge member when the gravitable body is in elevated position.

KOGEN MATSUKAWA.
